DESIGN FOR A VACUUM CLEANER OR SIMILAR ARTICLE

Leland H. Snyder, Chicago, Ill., assignor to
Quality Hardware and Machine Corporation,
Chicago, Ill., a corporation of Illinois

Application May 17, 1945, Serial No. 119,591

Term of patent 14 years

(Cl. D9—2)

To all whom it may concern:

Be it known that I, Leland H. Snyder, a citizen of the United States and a resident of the city of Chicago, in the county of Cook and State of Illinois, have invented a new, original, and ornamental Design for a Vacuum Cleaner or Similar Article, of which the following is a specification, reference being had to the accompanying drawing, forming a part thereof.

On the drawing:

Fig. 1 is a side elevational view of the vacuum

cleaner, or similar article, showing my new design, parts of the handle and dust bag being shown fragmentarily for convenience of illustration; and

Figs. 2, 3 and 4 are, respectively, a front view, a side view opposite that shown in Fig. 1, and a top plan view of the housing only.

I claim:

The ornamental design for a vacuum cleaner or similar article, as shown.

LELAND H. SNYDER.
